ILLUMINABLE TELEPHONE DIAL ATTACHMENT

Edward F. Malesky, Buffalo, N.Y., assignor to Glar-Ban Corporation, Buffalo, N.Y., a corporation of New York

Filed Nov. 14, 1960, Ser. No. 62,835

Term of patent 14 years

(Cl. D26—14)

FIG. 1 is a front perspective view of an illuminable telephone dial attachment embodying my new design;

FIG. 2 is a side elevational view thereof, viewed from the left of FIG. 1;

FIG. 3 is a side elevational view thereof, viewed from the right of FIG. 1;

FIG. 4 is a top plan view thereof;

FIG. 5 is a bottom plan view thereof;

FIG. 6 is a side elevational view thereof, viewed from the top of FIG. 4; and

FIG. 7 is a side elevational view thereof, viewed from the bottom of FIG. 4.

The broken and dotted line disclosure is for illustrative purposes only.

I claim:

The ornamental design for an illuminable telephone dial attachment, substantially as shown and described.
